UNITED STATES PATENT OFFICE

JAMES S. BRENNAN, OF ATTLEBORO, MASSACHUSETTS

DESIGN FOR A COMBINED SPIRITUAL MASS CARD TRAY AND STAND THEREFOR

Application filed July 25, 1929. Serial No. 32,203. Term of patent 3½ years.

To all whom it may concern:

Be it known that I, JAMES S. BRENNAN, a citizen of the United States, residing at Attleboro, in the county of Bristol and State of Massachusetts, have invented a new, original, and ornamental Design for Combined Spiritual Mass Card Tray and Stand Therefor, of which the following is a specification, reference being had to the accompanying drawings, forming part thereof.

The figure is a perspective view of a combined spiritual mass card tray and stand therefor, showing my new design.

What I claim is:—

The ornamental design for a combined spiritual mass card tray and stand therefor, substantially as shown.

In testimony whereof I have affixed my signature.

JAMES S. BRENNAN.
